United States Patent Office

Des. 202,238
Patented Sept. 7, 1965

202,238

STAPLE REMOVER OR SIMILAR ARTICLE

Sheldon I. Kohen, Flushing, and Nathaniel M. Olney,
New York, N.Y., assignors to Swingline, Inc., Long Is-
land City, N.Y., a corporation of New York

Filed Jan. 29, 1964, Ser. No. 78,403

Term of patent 14 years

(Cl. D74—1)

FIG. 4

FIG. 5

FIG. 1 is a side elevational view of a staple remover showing our new design, the side opposite thereto being similar in appearance.

FIG. 2 is a top plan view thereof.

FIG. 3 is a bottom plan view thereof.

FIG. 4 is a front elevational view thereof.

FIG. 5 is a rear elevational view thereof.

The portions of the staple remover not disclosed are similar to the portions of the staple remover shown.

We claim:

The ornamental design for a staple remover or similar article, as shown and described.
